UNITED STATES PATENT OFFICE.

JAMES ROBINSON FOGG, OF KENNETT SQUARE, PENNSYLVANIA.

ROCK-CRUSHER.

No. 904,946.

Specification of Letters Patent.

Patented Nov. 24, 1908.

Application filed June 20, 1907. Serial No. 379,961.

To all whom it may concern:

Be it known that I, JAMES ROBINSON FOGG, a citizen of the United States, residing at Kennett Square, in the county of Chester and State of Pennsylvania, have invented certain new and useful Improvements in Rock-Crushers; and I do hereby declare the following to be a full, clear, and exact description of the invention, such as will enable others skilled in the art to which it appertains to make and use the same.

My invention relates to rock crushers and particularly to the manner of operating the swinging jaw.

15 It aims to effect the crushing of the rock at a less expense of power and in such a way as to decrease the strain upon the machine and especially upon the lever for operating the swinging jaw.

20 Another object is to facilitate the feeding of the rock between the jaws.

The invention consists of the features of construction and combinations of parts hereinafter described and specified in the 25 claims.

In the accompanying drawings, illustrating the preferred embodiment of my invention: Figure 1 is a side elevation of the machine. Fig. 2 is a longitudinal vertical 30 section. Fig. 3 is a plan view, and Fig. 4 is a front elevation partly in section.

Referring more particularly to the drawing, 1 designates the side plates of the machine between which the fixed or stationary jaw 2 is bolted and which has grooves 3 formed therein to accommodate tongues or ledges on said fixed jaw whereby the bolts are saved from all strain. The swinging jaw 4 is mounted at its upper end on a shaft 35 extending between the side plates. The inner face of said swinging jaw above the die is convex so that there is no place for loose pieces and dust to collect as is the case when it is concave.

40 The lever 6 for actuating the swinging jaw is mounted at its upper end on an eccentric revoluble shaft 7 also having bearings in the side plates. Said lever bears near its lower end upon a roller 8 preferably 45 made of cast iron mounted upon a babbitted or bronze shaft 9. Said roller has a plurality of oil passages or compartments 10 closed by screw plugs 10^a. Said oil compartments are distributed around said roller whereby 50 it may always be kept thoroughly lubricated.

It is arranged nearly on a level with the toggle 11 but a little above the end of the lever so that said lever acts as a crow bar with the roller as a fulcrum and thereby accomplishes the maximum amount of work. 60 As the eccentric shaft to which the upper end of said lever is pivoted is arranged behind the vertical plane of the axis of the roller bearing, said lever is disposed on an incline and rests upon said roller bearing 65 above its horizontal axis. By arranging said lever on an incline, the desired crow bar action is obtained and the strain on the lever reduced to a minimum. Drive wheels 12 are mounted on the eccentric shaft and 70 a spring pressed rod 13 serves to retract the swinging jaw after each forward movement.

My invention is a great improvement over the old form of machine in which the operating lever is pivoted at its lower end and also over the form having vertically movable pendulum arms. I have found from practical experience that the pivot shaft in the first of these old constructions is subjected to so 75 much strain that it soon wears out and causes a great deal of trouble to replace it. In my construction the greatest strain comes upon the loose roller bearing 8 which may be kept well oiled, and which will revolve under the 80 action of the lever so that the wear will be evenly distributed. Said roller will accordingly last for a considerable time and when necessary may be easily replaced by knocking out the shaft on which it is mounted 85 without interfering with the lever which may be simply propped up out of the way while the change is being made.

The main defect in the type of machine employing a vertically movable pendulum 90 arm is that the strain comes at weak places, namely on the caps over the eccentric shaft with the result that said caps are frequently broken off. My construction also overcomes this objection as the strain is only on the cap 95 14 when the lever is on its back stroke and even then it is relieved by the retracting rod.

I claim:

1. In a rock crusher, the combination, with a fixed jaw, of a swinging jaw pivoted at its upper end, and an inclined operating lever having its upper end mounted on an eccentric shaft and its lower end having bearing connection with said swinging jaw, the bearing of said lever around said eccentric shaft 100 105 110

conforming to the shape of said shaft, said lever resting upon a fulcrum bearing at a point intermediate of its end.

2. In a rock crusher, the combination, with
5 a fixed jaw, of a swinging jaw pivoted at its
upper end, and an inclined operating lever
having its upper end mounted on an eccentric
shaft and its lower end having bearing
connection with said swinging jaw, the bearing
10 ing of said lever around said eccentric shaft

conforming to the shape of said shaft, said lever resting upon a roller fulcrum bearing at a point intermediate of its ends.

In testimony whereof, I affix my signature, in presence of two witnesses.

JAMES ROBINSON FOGG.
